UNITED STATES PATENT OFFICE.

AUSTIN GUDMUNDSEN AND FRANK E. DOLE, OF SALT LAKE CITY, UTAH.

SORTING DEVICE FOR LAUNDRY WORK.

Application filed May 5, 1924. Serial No. 711,032.

To all whom it may concern:

Be it known that we, AUSTIN GUDMUNDSEN and FRANK E. DOLE, citizens of the United States, residing at Salt Lake City, 5 in the county of Salt Lake and State of Utah, have invented certain new and useful Improvements in Sorting Devices for Laundry Work, of which the following is a specification.

10 Our invention relates to sorting devices used in laundry work and has for its object to provide a new, economical and conveniently operated pin which is detachably fastened in articles of clothing for marking 15 said articles while they are being washed in laundries.

A further object is to provide a locking laundry pin from which articles may be suspended, and from which said articles may 20 be detached by a simple lateral movement of either the articles or the pins while the articles or pins are bunched, and to sort and assemble said pins for replacement in their respective holders or cases whereby 25 articles of laundry may be accurately sorted, thereby saving the time and effort usually expended in removing the pins and placing them individually in their respective cases.

30 These objects we accomplish with the device illustrated in the accompanying drawings in which similar letters of reference indicate like parts throughout the several views, and as described in the specification 35 forming a part of this application and pointed out in the appended claims.

In the drawings in which we have shown the best mode of applying the invention to practical and beneficial use, Figure 1 is a 40 side elevation of the sorting device. Figure 2 is a side elevation of the opposite side of the sorting device with some of the pins shown thereon and unlocked, and with one pin locked, and before an article of clothing 45 which is held by the locked pin has been released. Figure 3 is an end elevation of the sorting device and a locked pin shown thereon. Figure 4 is a side elevation of the opposite side of the pin from that shown in 50 Figure 3. Figure 5 is a side elevation of the pin showing it unlocked. Figure 6 is an

edge view of the pin case. Figure 7 is a side elevation of hook portion of the pin.

In using laundry marking pins it is desirable that the pins may be sorted and assembled when not in use in their respective and proper cases. We provide an absolutely accurate means of sorting, checking and unpinning the articles, thereby saving the time usually expended in removing the individual pins and proving and checking them, and the operation of returning them to their respective cases, and checking against misplaced articles in the laundry.

The device consists of a thin metal plate A having an opening B medially therein which is shaped to conform with the shape of the supporting rod on which the pin and clothing thereon are suspended. A guide case C is provided by bending portions of said plate 70 A to form a rectangular case. The sides of said guide case are spaced apart to allow the parallel portion 1 of the hook to slide freely in said case. In the outer edge of said guide case C a recess D is cut. On the opposite edge of said case A a hook point case E is provided by bending other portions of said plate A to form the sides and ends, as shown at E in Figures 4 and 5, and said case E is extended from the body of said plate A as an integral wing portion to allow the hook point to be engaged when the clothing is suspended thereon. The hook portion of our device is a wire bent in the form of the letter S with portions parallel 80 as at 1, and one part tapered and ground to a point, as at 3, which is adapted to engage in the case E. The free end of the wire is bent away from the parallel portion to form a catch 2 which engages in said recess 90 D of the guide case to lock the pin. Key ways G are cut in the edges of said plate A, and a proving case H is provided having key lugs extending toward the central opening B of the plate A. The proving case 95 consists of a piece of tubing 4 adapted to slide over the free end of the supporting rods, and a guide strip 5 which are fastened to each other and spaced apart in parallel position by the base 16, which has a central opening in alignment with the interior of said tube 4. A rib 6 is provided longitudi-

nally on the side of said guide strip 5 adjacent the tube 4, against which the pins are to be moved to release the catch 2 and allow the hook to drop to the position shown in Figure 5. Transverse slits 7 are cut in the upper edge of said guide strip 5 to indicate to the operator when all pins belonging to that bunch of pins are in place on said tube 4. A testing clip F is pivoted on the outer 10 face of said guide strip 5, and a portion of said clip is bent to form a rectangular pin proving or testing members having a top and sides with open bottom, as shown in Figure 3. Key ribs 10 are secured on the inner faces of the top and one side, spaced respectively to fit the key ways G of the said plate A, and the position of the said key ribs and key ways are to be changed to the different devices used, as are the keys and 20 tumblers of a lock, in order that only pins having identical key ways may be passed over the tube 4 and pass the key ribs of one device. The key ribs 10 of all the other testing clips F are positioned differently and 25 in conformity to the changed position of the key ways of other plates. A rib or lug 11 is also extended from the top portion of said testing clip F which engages the inner face of said guide strip 5 and thereby prevent 30 any play of said testing clip F.

The operation of our device is as follows:—

The hook portion of the device is independently constructed, as shown in Figure 35 7, and its shank portions 1 are slipped into the guide case C by a slight flexing of the catch portion 2; the said shank is made of spring metal to allow the bending required. The flat shape given to the shank 1 or parallel portions when in the guide case C will 40 position the point of the hook in alinement with the case E, and when the catch 2 is below and free of the recess D the hook point will be spaced far enough from the 45 said case E to allow articles of clothing to be impaled on or engaged with said hook 3. The shank 1, with its integral hook 3, is then moved longitudinally toward the said plate and the catch 2 engaged in the recess 50 D, and when so engaged the point of the hook will be engaged in the case E and the clothing held on the hook. After the clothing has been laundered, the tubes 4 with the 55 attached guide plate 5 and base 6 are suspended from the supporting rods; then, by slipping the pins over the free end of said rod and tube 4, along the said rod and tube 4 through the opening B of each plate A and the plate through the testing clip F, which may be done only when the key ribs 60 10 fit the key ways 11 in the plates A the pins will be sorted. When all of the articles of one bunch of laundry are thus suspended on one rod and tube, the clothing 65 will be bunched and the devices will be

sorted and may be grasped with one hand by the operator while the bunch of laundered clothing is held with the other hand. Then, by a lateral movement of the clothing, each of the devices will be partially rotated on the supporting rod and the catches 2 will all be brought into contact with the rib 6 on the guide plate 5, whereby the catches 2 will be released and pushed from the recesses D, and the hooks 3 will be slid 70 downwardly and the clothing released from the hooks. The pins may then be quickly and easily removed from the supporting rod by turning the testing clip F upwardly on its pivot, as shown in dotted lines in Figure 80 1, which leaves the pins free for removal from the tube 4 for engagement with other articles to be laundered, and the tubes 4 with their attachments and carrying the pins 85 may be removed from said supporting rods and filed in cases kept for that purpose.

Having thus described our invention, we desire to secure by Letters Patent and claim:—

1. A laundry pin comprising a plate having a hole centrally therein and key ways in its edges; a guide case on one face thereof having a recess in its edge; a pin slidable in said case with one portion adapted for operation through said recess to lock and unlock another portion shaped as a point; a base having a tube secured thereon on which said plate is slidable; a guide strip secured on said base parallel with said tube; a longitudinal rib on said guide strip against which said pin may be moved to unlock it; a testing clip pivoted on said guide strip having key ribs on its inner face over which said recesses in said plate may be moved.

2. A laundry pin comprising a plate having an opening centrally therein with a portion forming a recessed guide case integral with one edge; and key ways in its other edges; a point case on the opposite edge; a pin slidable in said guide case with its point bent to engage in said point case; a guide strip having a longitudinal rib thereon adapted to unlock said pin and allow it to slide in its guide case; and a testing clip having ribs over which said key ways may be passed.

3. A laundry pin comprising a plate having notches in its edges and an opening centrally therein; a guide case having a recess cut in one edge thereof; a pin made of spring material having a hook on one end and a portion slidable in said guide case with one portion curved to engage in the recess in said guide case; a base having a tube secured thereon; a guide strip secured on said base having a longitudinal rib extended from one face thereof; a testing clip pivoted on said guide strip and having key ribs extended therefrom over which the notches in said plate may be passed.

4. A sorting laundry pin comprising a plate having notches in its edges; a pin operatively connected with said plate; a testing clip conforming on its interior with the shape of said plate's outer edges; and key ribs inwardly extended on said testing clip, and so positioned that they will pass

through said notches when the said plates are moved through said clip.

In testimony whereof we have affixed our ¹⁰ signatures.

AUSTIN GUDMUNDSEN.
FRANK E. DOLE.
